DESIGN FOR A DIAMOND OR SIMILAR ARTICLE

George Fine, New York, N. Y.

Application November 6, 1944, Serial No. 116,193

Term of patent 14 years

(Cl. D45—1)

To all whom it may concern:

Be it known that I, George Fine, a citizen of the United States and residing at New York, in the county of New York and State of New York, have invented a new, original, and ornamental Design for a Diamond or Similar Article, of which the following is a specification, reference being had to the accompanying drawing, forming part thereof, and in which

Fig. 1 is a top plan view of a diamond or similar article showing my new design,

Fig. 2 is a side view thereof, and

Fig. 3 is a bottom plan view thereof.

I claim:

The ornamental design for a diamond or similar article, substantially as shown.

GEORGE FINE.
